UNITED STATES PATENT OFFICE

113,549

DESIGN FOR A BOTTLE OR SIMILAR ARTICLE

Georges Chevalier, Vitry-sur-Seine, France, assignor to Guy T. Gibson, Inc., New York, N. Y.

Application July 5, 1938, Serial No. 78,263

Term of patent 14 years

To all whom it may concern:

Be it known that I, Georges Chevalier, a citizen of France, residing in Vitry-sur-Seine, France, have invented a new, original, and ornamental Design for a Bottle or Similar Article, of which the following is a specification, reference being had to the accompanying drawing, forming part thereof, wherein,

Figure 1 is a perspective view of a bottle or similar article showing my new design; and

The appearance of the sides of the bottle opposite to those shown in Fig. 1 are the same as the sides shown.

I claim:

The ornamental design for a bottle or similar article, substantially as shown and described.

GEORGES CHEVALIER.
